Primary Examiner — Mark Goodwin(74) *Attorney, Agent, or Firm* — Frost Brown Todd LLC**CLAIM**

The ornamental design for a tray, as shown and described.

DESCRIPTION

FIG. 1 is a top perspective view of a tray, showing our new design;

FIG. 2 is a bottom perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken line showing of the tray elements is included for the purpose of illustrating portions of the tray and forms no part of the claimed design.

UNITED STATES PATENT AND TRADEMARK OFFICE
CERTIFICATE OF CORRECTION

PATENT NO. : D723,392 S
APPLICATION NO. : 29/478780
DATED : March 3, 2015
INVENTOR(S) : Shoshan et al.

Page 1 of 1

It is certified that error appears in the above-identified patent and that said Letters Patent is hereby corrected as shown below:

On the Title page

Item (12) should read --Shoshan et al.--

Item (72) Inventor(s) - should be deleted:

“Gandhi B. Sifuentes, West Covina, CA (US);
Craig R. Snedden, Culver City, CA (US);
Tal Shoshan, Alta Loma, CA (US)”

- and be replaced with:

Tal Shoshan, Alta Loma, CA (US);
Gandhi B. Sifuentes, West Covina, CA (US)

Signed and Sealed this
Eighth Day of September, 2015

Michelle K. Lee
Director of the United States Patent and Trademark Office
